United States Patent Office

Des. 179,649
Patented Feb. 5, 1957

179,649

TABLE

John A. Maddox, Virginia Beach, Va.

Application June 29, 1956, Serial No. 42,087

Term of patent 14 years

(Cl. D33—14)

FIG. 1

I claim:

The ornamental design for a table, as shown.
